STENCILING MACHINE FOR APPLYING
LUMINOUS PAINTRufus G. Fordyce, Glencoe, Ill., assignor to
Luminous Processes, Inc., Chicago, Ill., a corpora-
tion of Delaware

Application October 10, 1946, Serial No. 702,557

15 Claims. (Cl. 101—123)

1

This invention relates to means for applying paint, and it is particularly concerned with the problem of applying luminous paint of the character used on the dials of clocks and watches and for some other purposes.

One object of the invention is to provide a new and improved mechanism by which such paint can be applied through a stencil of the silk screen type.

Another object of the invention is to provide a new and improved mechanism having adjustable pressure means for forcing the paint through a silk screen stencil.

It is also an object of the invention to provide a paint applying machine including a silk screen stencil and a rotary squeegee device operative to force the paint through such stencil and to make efficient use of the paint supplied thereto.

An additional object of the invention is to provide a machine for applying luminous paint in which the paint is confined in a substantially closed chamber and is fed therefrom through a silk screen stencil onto the surface to be decorated.

More specifically, the invention provides a machine for applying luminous paint and including a stencil of the silk screen type and a squeegee mounted for rotation against the screen, together with driving means for the squeegee and control means adapted to limit it to a single rotation when actuated, thereby insuring uniformity in the work produced.

Other objects and advantages of the invention will appear from the following description considered in connection with the accompanying drawings, in which:

Fig. 1 is a front elevation of a machine embodying this invention, lower portions of the frame being broken away to somewhat condense the view;

Fig. 2 is a side elevational view of the machine shown in Fig. 1, with parts broken away in the lower portion;

Fig. 3 is a vertical sectional view taken as indicated at line 3—3 on Fig. 2 and on a larger scale;

Fig. 4 is a plan sectional view taken as indicated at line 4—4 on Fig. 3;

Fig. 5 is a detail section taken as indicated at line 5—5 on Fig. 3;

Fig. 6 is a fragmentary detail taken as a section at line 6—6 on Fig. 5;

Fig. 7 is a horizontal detail section taken as indicated at line 7—7 on Fig. 3;

2

Fig. 8 is a fragmentary detail section taken as indicated at line 8—8 on Fig. 7;

Fig. 9 is a detail section taken as indicated at line 9—9 on Fig. 7;

5 Fig. 10 is a fragmentary plan view of the work-supporting carriage;

Fig. 11 is a side elevational view taken partly in section as indicated at line 11—11 on Fig. 10.

Fig. 12 is a fragmentary detail view partly in section showing a modified arrangement for applying adjustable pressure to the squeegee blades; and

Fig. 13 is a detail sectional view taken substantially as indicated at line 13—13 on Fig. 12.

15 The drawings illustrate a machine which is adapted to apply luminous paint to a flat surface, either as a decoration or to serve a useful function, as in the case of a watch or clock dial. The frame of the machine includes upright leg members 10 supporting horizontal members 12 provided with a cover plate 14 which may be used as a table surface for work pieces to be treated by the machine. Within an open middle portion of the table area there is mounted a carriage 15 which may be fitted with any suitable work-holding or positioning devices, such as clamps, jigs, lugs or pins. Fig. 1 indicates a work piece such as a clock dial in dotted outline at A, and also shows a locating and supporting fixture B mounted on the carriage 15. Said carriage 15 surmounts a yoke 16 which is guided by rods 17, 17 for vertical reciprocation and is arranged to be actuated by means of a treadle bar 18 carried by a pair of levers 19, which are fulcrumed on the frame at 20 and connected by a link 21 to a lever 22. One end of the lever 22 is connected by a pivot 23 to a bifurcated coupling 16a extending from the yoke 16, and the opposite end of the lever may carry a counterweight 22a to insure easy action of the treadle.

Bracket members 24, 24, extending upwardly from the level of the table 14, support the paint chamber 26. The bottom wall 28 of the chamber spans the space between the brackets 24, 24 and is reinforced by the vertical walls 30 and 32 which have triangular end portions 34 extending beyond the paint chamber proper. The side walls 36 of the paint chamber extend above the top wall 38 thereof to support a platform 40 on which a driving motor 42 is mounted. To afford access to the interior of the paint chamber, the walls 30 and 32 are provided respectively with removable cover plates 44 and 45, and with gas-kets therefor.

45 As shown in Fig. 3, the bottom wall 28 of the

3

paint chamber 26 has an opening 46 below which there is mounted the silk screen stencil 48 through which the paint is to be applied to an object or workpiece supported on the carriage 15. The stencil layer 50 having cut-out portions corresponding to the design to be applied is secured to the under surface of the screen 52, and the stencil screen 48 thus formed has its marginal portions clamped to a frame 54 which, in turn, is secured by clips 56 to the underside of the bottom wall 28 in a position to cover the opening 46 therein.

Paint is supplied from a reservoir 58 which may be mounted on a suitable support 60 extending upwardly from one of the brackets 24, as seen in Fig. 1. A stirring device 62 is provided with a crank handle 64 by which it may be manually actuated intermittently as required, and a feed pipe 66 leads from the bottom of the reservoir 58 into the paint chamber 26 to a point of discharge directly over the stencil screen 48. Paint of luminous character tends to produce some gaseous fumes such as Radon gas, and this is one reason for having the paint chamber substantially closed. To carry off these fumes, an exhaust pipe 68 is shown leading from the chamber 26, and this pipe may be connected by a flexible hose 70 to a suitable exhaust fan, not shown, for discharging the fumes outside the building in which the machine is located.

The consistency of the paint and the gage of the silk screen 52 are such that the paint will not flow by gravity through the screen but must be forced through, preferably by means of a squeegee. For this purpose, the present invention provides a vertically disposed rotary shaft 72 which, as shown in Fig. 7, carries three radial arms 74 to each of which there is clamped a squeegee blade 76 of rubber or like material having a tapered lower edge 78 as seen in Fig. 9. A clamping block 80 and screws 82 serve to secure each squeegee blade 76 to its supporting arm 74, and preferably each of said arms 74 is bent to present a concave front face which gives the blade 76 a corresponding concave face at its forward side considered in relation to the direction of rotation of the shaft 72 and the arms 74. Thus, as the shaft rotates said arms with the squeegee blades 76 in contact with the stencil screen, said blades act to gather the paint and to force it through the screen along an annular path over which they sweep as they rotate. As hereinafter explained, the application of the paint to each object or workpiece is accomplished by a definitely limited rotation of the squeegee blade 76.

The shaft 72 is mounted with its axis substantially perpendicular to the plane of the stencil screen 48 and said screen is normally so mounted as to remain substantially flat; but to compensate for any possible irregularity in the screen or in its position, and also for any slight inequalities in the squeegee blades 76, the squeegee head, consisting of the arms 74 and the central hub 84, is mounted on the end of the shaft 72 in a manner which permits limited universal movement of the head. The lower end of the shaft is formed with a spherical surface 86 which engages the end wall 88 of the hub 84, and a spring 90 secured within the hub by a gland member 92 reacts against a shoulder 94 on the shaft 72 to maintain contact between the spherical surface 86 and the flat surface 88. A loose driving connection is provided by a

cross pin 96 in the shaft 72 engaging notches 98 in the gland member 92 of the hub. This arrangement permits the squeegee assembly to accommodate itself to the stencil screen so that all three blades 76 will bear evenly upon the screen as the shaft 72 is rotated. A steady bearing 75 for the shaft 72 is mounted in a cross bar 77 extending between the side walls 36.

As seen in Fig. 3, the motor 42 is shown associated with a housing 100 which may be understood as containing any suitable speed-reducing gearing and from which there extends a driving shaft 102 which is axially aligned with the shaft 72. Said shaft 102 carries the upper member 104 of a toothed clutch which is shown in elevation in Fig. 6, and the lower member 106 of such clutch is secured to a hollow shaft or sleeve 108 journaled in ball bearings 110 which are supported in a bracket 112 depending from the platform 40 on which the motor 42 is mounted. A spring 114 coiled about the sleeve 108 tends to urge the clutch member 106 into engagement with the clutch member 104 but such engagement is normally prevented by a latch 116 which is pivoted at 118 on the under side of the platform 40. A roller 120 projecting radially from the clutch member 106 engages under the cam surface 122 of the latch 116, as seen in Fig. 6, to hold the member 106 out of clutching position. By means of a link 124 connected to a bell crank 126 and actuating rod 128, the latch 116 may be withdrawn laterally out of engagement with the roller 120, thus permitting the spring 114 to lift the clutch member 106 into connection with the clutch member 104 which is rotated continuously by the motor 42. The rod 128 is connected to a rock shaft 127 having an operating handle 129 (see Fig. 2). As the handle 129 is released, the spring 130 will return the parts to their initial positions, shifting the latch 116 into place so that its cam face 122 will engage the roller 120 at the end of the first revolution of the clutch member 106, thus withdrawing said member 106 from the clutch member 104; and as seen in Fig. 6, the shoulder 123 of the latch 116 will engage the roller 120 to positively arrest the clutch member 106 and the sleeve 108 to which it is keyed.

The sleeve 108 is splined to the upper end of the shaft 72 at 132 so that whenever the clutch 104, 106 is connected as just described, the shaft 72 will make a single revolution, causing the squeegee blades 75 to sweep over the stencil screen 48 through a single turn, and this will be sufficient to apply a measured quantity of the paint through the stencil to the surface to be decorated. During this operation of the squeegee blades, said blades are held yieldingly against the upper surface of the stencil screen 48 by a spring 134 coiled about the shaft 72 and reacting between a collar 136 on said shaft, and a block 138 secured to the under surface of the top wall 38 of the paint chamber through which the shaft 72 extends upwardly. It is preferable, however, that when the squeegee blades 76 are at rest, they shall remain out of contact with the stencil screen, thus permitting the paint to flow evenly over it between operations. Therefore, a collar 140 is secured to the upper end portion of the shaft 72 and carries a radially extending stud 142 with a roller 144 thereon for engagement with an annular cam track 146 which encircles the shaft 72 and which is formed on the upper surface of a wedge block 148. Said cam track

is seen in section in Fig. 3 and a plan view thereof is presented in Fig. 4, the high portion of the track being indicated at 146a and the lower portion at 146b. As the roller 120 of the clutch member 106 encounters the cam surface 122 of the latch 116, the roller 144 will be relatively so positioned that it will ride onto the higher portion 146a of the cam track 146, thus lifting the shaft 72 so as to withdraw the squeegee blades 76 from the surface of the stencil screen. The splined connection between the shaft 72 and the sleeve 108 permits this endwise movement of the shaft. The collar 140 may be adjustable vertically on the shaft 72 along a threaded portion 72a thereof, but will be locked at adjusted position by means of a set screw 150 engaging in a key slot 72b in the shaft 72, as seen in Fig. 3.

It is of course important that when the squeegee blades 76 are lowered onto the stencil screen, they shall exert the required pressure to perform their function without unduly straining the screen or excessively flexing the blades themselves. The lower limit of movement of the shaft 72 is therefore rendered delicately adjustable by means of the slideable wedge block 152 disposed under the wedge block 148 to cooperate therewith in vertically adjusting the cam track 146. Said block 152 carries a threaded plate 154 secured to one edge of the block and engaging an adjusting screw 156 which is journaled in the side wall 36 with stop collars 158 preventing endwise movement of the screw and with a hand wheel 160 by which it may be turned for shifting the wedge block 152. The pressure applied by the spring 134 may be varied by adjusting the collar 136 along the threaded portion of the shaft on which it is secured.

In view of the fact that the stencil 50 is mounted in a fixed position, it is important that the workpiece such as that indicated at A in Fig. 1 shall be accurately positioned on the work support or carriage 15. Therefore, after a suitable jig or holding device, indicated in Fig. 1 at B, has been affixed to the upper surface of the carriage 15, it may be necessary to adjust this portion of the carriage to register the workpiece A properly with the design of the stencil 50. To permit such adjustment, the table 170 of the carriage 15 is supported rotatably upon a post or spindle 171 with roller bearings 172 and 173 interposed. The post 171 is extended rigidly from a cross slide 174 having an adjusting screw 175 and handwheel 176 for shifting it on a main slide 177. The slide 177 is similarly provided with an adjusting screw 178 and hand wheel 179 for shifting it in a transverse direction on its base 180. Rotative adjustment of the table 170 about the axis of the post 171 is effected by a handwheel 181 which operates a worm 182 engaging a worm gear 183 affixed to the underside of the table 170 as seen in Figs. 1 and 10. The base 180 on which the adjustable parts are carried is anchored to a pad 184 which is formed integrally with the yoke 16. With this arrangement, after the work holding fixture B has been secured in place on the table 170, the table may be adjusted by any desired amount either forward or backward or to the right or to the left, or it may be turned about the axis of the post 171 through any required angle so that a workpiece supported on the fixture B will come into proper relation with the stencil 50 when the carriage is elevated.

Figs. 12 and 13 illustrate a modified arrangement for providing any desired pressure between

the squeegee blades 76 and the stencil screen 48. Fig. 12 shows a fragment of what may be considered one of the side walls 36 of the paint chamber 26 and shows a rock shaft 190 which may be journaled in said side walls so as to extend through the paint chamber. Outside the chamber said rock shaft carries a lever arm 191, and there is secured to the wall 36 an angle bracket 192 in which the upright rod 193 is anchored, being threaded into the bracket at 194 and provided with a lock nut 195 to secure it. The lever 191 has a clearance opening 196, through which the rod 193 extends freely. A spring 197 is interposed between the bracket 192 and the underside of the lever 191, and a second spring 198 is interposed between the upper side of the lever 191 and an adjustable nut 199 on the threaded upper end of the rod 193.

Inside the paint chamber 26 the rock shaft 190 has a pair of arms 200 extending at opposite sides of the vertical shaft 72 which carries the squeegee head at its lower end. The shaft is provided with a thrust collar 202 with a ball bearing 204 interposed between said collar and the shaft 72 and anchored to the shaft between a flange 72a formed thereon and a securing nut 206. The collar 202 is connected to the lever arms 200 by pivots 207 and links 208, so that pressure or movement affecting the arm 191 is transmitted through the rock shaft 190, arms 200, links 208 and collar 202 to the shaft 72. The springs 197 and 198 thus operate in place of the spring 134 to provide the desired yielding pressure which holds the squeegee blades 76 against the stencil screen 48 during the rotation of the shaft 72. With this arrangement, the effective pressure on the shaft 72 may be delicately adjusted by means of the nut 199 which incidentally is accessible outside the paint chamber and is therefore more convenient than the collar 136 shown in Fig. 3 for adjusting the tension of the spring 134.

The ball bearing 204 which is mounted on the shaft 72 inside the paint chamber 26 is protected against any possible deposit of paint by means of a conical hood 210 secured to the shaft 72 by a set screw 211 so as to rotate with it. The sloping outer surface of the member 210 tends to shed the paint by gravity if any of it lodges thereon, and also tends to throw it off by centrifugal force when the shaft 72 is rotated.

While there is shown and described herein a combination of certain devices and mechanisms embodying the invention and illustrative thereof, it will be understood that the invention is not limited thereto or thereby but includes all modifications, variations and equivalents which may come within the scope of the appended claims.

I claim:

1. In a stenciling machine, means forming a substantially closed chamber including a stencil screen which serves as a wall of said chamber, a shaft journaled for rotation about an axis substantially perpendicular to the plane of the screen, a squeegee carried at the end of said shaft for rotation about the axis thereof and in contact with said screen, means providing a loose universal connection between said shaft and the squeegee for automatically compensating for deviation of the shaft or screen from planes perpendicular to each other, spring means adapted automatically to urge the shaft axially toward the screen, means for holding a work piece in contact with the stencil outside the chamber, and means to rotate the shaft and squeegee.

2. In a stenciling machine, a horizontally disposed stencil screen, a shaft journaled for rotation about an axis perpendicular to the plane of the screen, a squeegee carried at the end of said shaft for rotation thereby against the screen, a driving member for the shaft, yieldingly engageable clutch means to connect said shaft to the driving member, and latch means operative to disconnect said clutch and to arrest the shaft at a predetermined point in its rotation together with cam means operable automatically to shift said shaft axially as it rotates and formed to permit movement of the squeegee into contact with the screen during a portion of each rotation and to separate it from said screen during the remainder of the rotation.

3. In a stenciling machine, means forming a substantially closed chamber including a stencil screen which serves as a wall of said chamber, a shaft journaled for rotation about an axis substantially perpendicular to the plane of the screen, a squeegee carried at the end of said shaft in contact with said screen, a thrust collar journaled on said shaft, a rock shaft extending transversely of the first shaft in said chamber with one end of said rock shaft extending through a wall of said chamber, an arm on said rock shaft connected to said thrust collar, and adjustable spring means outside the chamber arranged to produce a torque in said rock shaft in a direction to urge the thrust collar and the other shaft toward the screen for pressing the squeegee into operative contact therewith.

4. In the combination defined in claim 3, said rock shaft having an arm outside the chamber and said spring means comprising a pair of springs engaging opposite sides of said arm, and abutment means for said springs, at least one of said abutments being adjustable to vary the torque transmitted to the rock shaft.

5. In a stenciling machine, a horizontally disposed stencil screen, a shaft journaled for rotation about an axis perpendicular to the plane of the screen, a squeegee carried at the end of said shaft for rotation thereby against the screen, a driving member for rotating the shaft, said shaft being axially movable and being normally positioned to hold the squeegee out of contact with the screen, control means including a clutch axially aligned with said shaft and driving member and yieldingly engageable with the latter to connect the same with said shaft, latch means operative to disconnect the clutch and arrest movement of the shaft, and shifting means including a cooperating cam and follower means on the shaft and machine for raising the shaft as it is arrested and thus separating the squeegee from the screen.

6. In a stenciling machine, a horizontally disposed stencil screen, a shaft journaled for rotation about an axis perpendicular to the plane of the screen, a squeegee carried at the end of said shaft for rotation thereby against the screen, spring means adapted automatically to urge the shaft axially toward the screen, means for shifting the shaft to hold said squeegee out of contact with the screen when the shaft is at rest including a cam and a follower therefor, one of said parts being fixed and the other being rotatable with said shaft, a driving member for the shaft, clutch means to connect said shaft to the driving member, and means to disconnect said clutch automatically at a predetermined position in the rotation of the shaft, said cam being formed to separate the squeegee from the screen

75 rotate said shaft and squeegee, means to arrest

as the shaft approaches said position in its rotation.

7. In a stenciling machine, a horizontally disposed stencil screen, a shaft journaled for rotation about an axis perpendicular to the plane of the screen, a squeegee carried at the end of said shaft for rotation thereby against the screen, spring means adapted automatically to urge the shaft axially toward the screen, means for shifting the shaft to hold said squeegee out of contact with the screen when the shaft is at rest including a cam and a follower therefor, one of said parts being fixed and the other being rotatable with said shaft, a driving member for the shaft, clutch means to connect said shaft to the driving member, and latch means operative to disconnect said clutch and to arrest the shaft at a predetermined point in the rotation of said shaft, said cam being formed to shift the shaft for separating the squeegee from the screen at said point in the operation of said shaft.

8. A stenciling machine including in combination a horizontally disposed stencil screen, a shaft journaled for rotation about an axis normal to the plane of the screen, means for intermittently rotating said shaft, a squeegee carried by said shaft for rotation against the screen, yieldable means for biasing the shaft and squeegee for axial movement toward said screen, means for moving said shaft axially in opposition to said yieldable means to separate the squeegee and screen when the shaft comes to rest and to free the shaft for movement toward the screen when said shaft starts rotating including stationary cam means and cooperating cam means rotated by said shaft, and means accurately to adjust the limits to which said shaft and squeegee move axially relative to the screen including wedge blocks to support said stationary cam means having reversely inclined faces disposed in superposed relation, said blocks being adjustable to bring more or less of the inclined faces into superposed relation, thereby to raise or lower the stationary cam and the limits to which the shaft moves axially relative to the screen.

9. In a stenciling machine, a stencil screen, a shaft journaled for rotation about an axis normal to the screen, a squeegee carried on one end of said shaft for rotation thereby against the screen, driving means to rotate said shaft and squeegee, means to arrest rotation of said shaft and render said driving means inoperative to rotate said shaft each time the squeegee has been rotated far enough to complete a stenciling operation, a spring to bias the shaft in a direction to move the squeegee into stenciling relationship with the screen, cam means to move the shaft axially in opposition to the spring including a fixed part and a part engaged thereby and rotatable by said shaft, said parts cooperating to move the shaft axially in a direction to separate the squeegee from the screen when the squeegee completes a stenciling operation and to free the shaft for movement of the squeegee into stenciling relationship with the screen under the influence of said spring when the shaft starts rotating, and means to adjust the cam means axially of the shaft to vary the limits to which the shaft and squeegee move axially relative to the screen.

10. In a stenciling machine, a horizontally disposed stencil screen, a shaft journaled for rotation about an axis normal to the screen, a squeegee carried on one end of said shaft for rotation thereby against the screen, driving means to

rotation of said shaft and render said driving means inoperative to rotate said shaft each time the squeegee has been rotated far enough to complete a stenciling operation, a spring to bias the shaft and squeegee toward the screen, means to adjust said spring to increase or decrease the biasing force exerted thereby, and cam means to move the shaft axially in opposition to said spring including a fixed part and a part engaged thereby and rotatable by said shaft, said parts cooperating to move the shaft axially in a direction to separate the squeegee from the screen when the squeegee completes a stenciling operation and to free the shaft for movement of the squeegee into stenciling relationship with the screen under the influence of said spring when the shaft starts rotating.

11. In a stenciling machine a horizontally disposed stencil screen, a shaft journaled for rotation upon an axis normal to the screen, a squeegee carried on one end of said shaft for rotation thereby against the screen, driving means to rotate said shaft and squeegee, means to arrest rotation of said shaft and render said driving means inoperative to rotate the shaft each time the squeegee has been rotated far enough to complete one stenciling operation, yieldable means to bias said shaft and squeegee toward said screen, means to adjust the biasing force exerted by said yieldable means, and means rendered effective by rotation of said shaft as the squeegee completes a stenciling operation to move the shaft axially in a direction to separate the squeegee and screen and to free the shaft for movement of the squeegee into stenciling relationship with the screen under the influence of said spring when the shaft starts rotating.

12. In a stenciling machine a stencil screen, a shaft journaled for rotation about an axis normal to the plane of the screen, a squeegee carried at the end of said shaft for rotation thereby against the screen, means to rotate said shaft intermittently, a coil spring surrounding said shaft and reacting between a stationary part of said machine and said shaft to bias the latter and said squeegee toward the screen, means to adjust said spring to increase or decrease the axial thrust on said shaft, cam means to move the shaft axially in opposition to said spring including a part on said machine surrounding said shaft and a part rotatable with said shaft to move the shaft axially in a direction to separate the squeegee from the screen at a predetermined point in the rotation of said shaft and to free the shaft for movement into contact with the screen under the influence of said spring at another predetermined point in the rotation of said shaft.

13. A stenciling machine comprising means forming a substantially fluidtight gas collecting chamber including a stencil screen forming at least a portion of one wall of said chamber, a shaft journaled for rotation about an axis perpendicular to the plane of the screen and having at least a portion thereof extending into said chamber, a squeegee in the chamber secured to the shaft for rotation thereby against the screen, a driving member for rotating said shaft, said shaft being axially movable and being normally positioned to hold the squeegee out of contact with the screen, clutch means yieldingly engageable with the driving member to connect the same with said shaft, latch means operative to dis-

connect the clutch and arrest movement of said shaft, means to shift the shaft axially, including cooperating cam and follower means on the shaft and machine for moving the shaft axially as it is arrested in a direction to separate the squeegee from the screen, and means for holding work to be stenciled in contact with the stencil screen on the outside of said chamber.

14. A stenciling machine including in combination means forming a substantially fluidtight gas collecting chamber including a stencil screen forming at least a portion of one wall of said chamber, a shaft journaled for rotation about an axis perpendicular to the plane of the screen and including a part extending into said shaft in the chamber for rotation thereby against the screen, driving means to rotate said shaft and squeegee, means to arrest rotation of said shaft and render said driving means inoperative to rotate the shaft each time the squeegee has been rotated far enough to complete one stenciling operation, yieldable means to bias said shaft and squeegee toward said screen, means to adjust the biasing force exerted by said yieldable means, means rendered effective by rotation of said shaft as the squeegee completes a stenciling operation to move the shaft axially in a direction to separate the squeegee and screen and to free the shaft for movement of the squeegee into stenciling relationship with the screen under the influence of said spring when the shaft starts rotating, and means for holding work to be stenciled in contact with the stencil screen on the outside of said chamber.

15. In a stenciling machine, a stencil screen, a shaft journaled for rotation upon an axis normal to the plane of the screen, a squeegee assembly on said shaft including a central hub, a plurality of rigid generally radially extending arms fixed to said hub and a flexible squeegee blade fixed to each arm for wiping contact with the screen when the shaft is rotated, the ends of said blades being turned forward with respect to the direction of rotation of the shaft, yieldable means to bias said shaft and squeegee toward said screen, driving means to rotate the shaft, means conditioned manually to connect said shaft and driving means and automatically to disconnect the same at a predetermined point in the cycle of rotation of said shaft, and means operable automatically to move said shaft axially in a direction to separate the squeegee and screen at said predetermined point in the rotation of the shaft.
